Marshall J. Rohr

By

Scott Snyder Attorney

UNITED STATES PATENT OFFICE.

MARSHALL J. ROHR, OF WASHINGTON, DISTRICT OF COLUMBIA.

DESIGN FOR A TOY.

• **55,958.**

Specification for Design.

Patented Aug. 3, 1920.

Application filed June 1, 1916. Serial No. 101,185. Term of patent 3½ years.

To all whom it may concern:

Be it known that I, **MARSHALL J. ROHR**, a citizen of the United States, and a resident of Washington, in the District of Columbia, have invented a new original, and ornamental Design for Toys, for which the following is a specification, reference being had to the accompanying drawing, forming a part thereof.

The figure is a top plan view of a toy showing my design.

I claim:

The ornamental design for a toy as shown.

MARSHALL J. ROHR.
